UNITED STATES PATENT OFFICE.

CHRISTOPHER WEATHERSON, OF CHICAGO, ILLINOIS; SARAH J. WEATHERSON EXECUTRIX OF SAID CHRISTOPHER WEATHERSON, DECEASED.

AXLE-FORGING APPARATUS.

Application filed October 1, 1919. Serial No. 327,633.

To all whom it may concern:

Be it known that I, CHRISTOPHER WEATHERSON, a citizen of the United States, residing at Chicago, in the county of Cook and 5 State of Illinois, have invented certain new and useful Improvements in an Axle-Forging Apparatus, of which the following is a specification.

My invention relates to an axle manipulating device and has particular reference to a device for use in the forging operation incident to the manufacture of car axles.

One of the objects of the invention is the provision of a device which will handle the 15 axle during the entire forging operation without the assistance of tongs, as has been the practice heretofore.

Another object of my invention is the provision of an apparatus which will keep 20 the axle blank out of contact with the forging dies, except for the brief period when the dies are actually working upon the axle blank. It has been the practice heretofore to place an axle blank between a pair of reciprocating dies, one of which supports 25 the axle blank all of the time, even while the workmen by the assistance of tongs turn the blank to complete the forging operation. Because of the fact that the axle blank is forged hot while it is resting upon 30 the die it loses a considerable amount of heat and makes the forging of the axle more difficult. By my improved device this loss of heat is eliminated as the axle is only in contact with the lower die during the time 35 when the blank is being worked by the dies and the forging of the axles is completed at a higher heat, thus insuring better quality in the axles.

Another and further object of my invention is the provision of a device which will materially lessen labor and will enable the workmen to handle the blank during the forging operation much more quickly and expeditiously than has been the practice 45 heretofore.

Still another object of my invention is the provision of a forging apparatus which 50 will completely form a car axle without the aid of a straightening machine and also without the necessity of caliper the axle during the forging operation, as the axle is forged down until the die faces are in contact and the axle being constantly turned 55 during the forging operation is practically

straight so there is no necessity of using a straightening machine.

Another and further object of my invention is the provision of an apparatus which will be simple and efficient in operation, 60 positive in its action and which will control the axle blank from the beginning of the forging operation until the blank is forged into a completed axle. These and other objects of my invention will be more fully and 65 better understood by those skilled in the art by reference to the accompanying drawings, and in which:—

Figure 1 is a general plan view of my improved invention: 70

Figure 2 is an end elevation of the rear end thereof;

Figure 3 is a side view in elevation;

Figure 4 is a sectional view on lines 4—4 75 of Figure 1;

Figure 5 is a sectional view showing the method of mounting the table upon the frame; and

Figure 6 is a sectional view of one of the single acting cylinders for operating the 80 gripping device.

Referring now specifically to the drawings, a foundation 10 of concrete or other suitable material is shown to which is secured a base or frame 11 in any suitable manner as by bolts 12. Vertical columns 13, 14, 15 and 16 are shown which support the forge press (not shown). A sliding table 17 is mounted upon projections 18 integrally with the frame 11, the said projections having V-shaped tops within which suitable slides 20, 20 secured to the table are mounted. A shaft 21 is carried by the sliding table 17 upon the ends of which are mounted levers 22 and 23. Counter-weights 24 and 95 25 are mounted upon the rear end of the levers 22 and 23 respectively and are adjustably held in position by means of screws 26, 26 upon the forward ends of the levers 22 and 23. A pair of single acting cylinders 27 and 28 are mounted in the ends of the levers 22 and 23, a sectional view of one of these cylinders being shown in Figure 6. Piston rods 29 extend completely through the cylinders and have 100 pistons 30 mounted thereon, one end of the piston rods 29 being pointed or sharpened so that they will engage the end of the axle blank as hereinafter described, and having 105 a hand wheel 33 mounted upon the outer 110

end of one of the piston rods for purposes hereinafter described. The piston rods 29 pass through the cylinder heads 32 and through the inner end of the cylinders, glands 31 being secured in the inner end of the cylinders and which serve as guides for the piston rods 29. An opening 34 is provided in the cylinder head 32 through which fluid pressure is admitted to the cylinder and which serves to drive the piston rods 29 inwardly into engagement with the axle blank as hereinafter described. A suitable gland 35 is provided in the cylinder head 32 and which surrounds the piston rod 29, the gland 35 being held in position by a cap 36 which is in threaded engagement with the cylinder head 32 in the usual manner. A fluid pressure supply 37 is provided which leads to each of the cylinders 27 and 28, the pipe 37 being connected to the cylinder heads at the opening 34 for the purpose of admitting fluid pressure to the cylinders 27 and 28. A vent 31^a is provided in each of the cylinders near their inner ends to allow for the free passage of air in and out of the cylinders.

Mounted on each side of the table 17 is a pair of single acting cylinders 40 and 41, the said cylinders being secured to the table 17 by means of bolts 38 passing through the side of the table 17 and bracket portions 39 of the cylinders 40 and 41 and having piston rods 42 and 43 extending therethrough, the piston rods having the usual pistons mounted thereon which reciprocate in the cylinders 40 and 41. Heads 44 and 45 are provided which are in threaded engagement with the upper ends of the cylinders 40 and 41 respectively, and which serve as guides to the piston rods 42 and 43. The piston rods 42 and 43 extend through the cylinders 40 and 41 and have a pair of lock nuts 46 on their lower ends, which nuts serve to limit the travel upward of the piston rods for the purposes hereinafter described. A fluid pressure line 47 is provided for the purpose of supplying pressure to each of the cylinders 40 and 41.

Suitably mounted upon the frame 11 is a double acting cylinder 48 having a piston rod 49 located therein to which is secured a piston 50, the said piston rod 49 at its forward end being secured to a projection 51 extending downwardly from the sliding table 17 and integral therewith. A bolt 52 having a lock nut 53 thereon extends through the rear cylinder head 54 of the cylinder 48 and provides means for limiting the extent to which the cylinder head 50 may travel rearward of the cylinder. Fluid pressure is supplied to the cylinder 48 through pressure lines 55 and 56 respectively, the line 55 admitting fluid pressure to the rear of the cylinder 48 and the line 56 admitting pressure to the forward end of the

said cylinder 48 for the purpose of moving the table 17 forward and backward as hereinafter described. Secured to the columns 14 and 15 respectively is a pair of brackets 57 and 58 to the outer ends of which is secured a bracket 59. Upon this bracket is mounted a pair of three-way valves 60 and 61 which control the admission and outlet of fluid pressure to the lines 37 and 47 respectively. A four-way valve 62 is also secured to this bracket 59 and which controls the pipe lines 55 and 56. A pair of V-shaped brackets 63 and 64 are provided which are secured to the frame 11 by means of bolts 65 or in any other suitable manner. A pair of reciprocating upper and lower forging dies 66 and 67 respectively are provided having adapted thereto suitable operating mechanism (not shown) which forms no part of my present invention. A pair of inclined skids 68 and 69 are provided upon which the axles are placed after the forging operation is complete and which lead to the loading platform or to any other place desired.

As will be apparent from the foregoing description, the operation of the device is comparatively simple. A blank or axle billet 70 which has been rolled to a suitable diameter and cut to the proper length is placed upon the V-shaped supports 63 and 64. The table 17 in the meantime has been brought to a point where the piston rods 29 carried by the cylinders 27 and 28 respectively are brought into a position centrally located with respect to the axle blank by means of fluid pressure admitted to the forward end of the cylinder 48 through the four-way valve 62. This position of the table 17 is controlled by the bolt 52 which is adjusted to such position that when the piston 50 abuts against the bolt 52, the gripping ends of the piston rods 29 are centrally located of the axle blank 70. The bolt 52 can also be adjusted so as to properly position the gripping cylinders for axle blanks of different sizes or diameters. Pressure is then admitted to the cylinders 27 and 28 through the line 37 under the control of the three-way valve 60, so that the piston rods grip and securely hold the axle blank in proper position.

The gripping cylinders 27 and 28 are brought to proper position as to height by means of pressure admitted to the cylinders 40 and 41 through the line 47 which is under control of the three-way valve 61. The height to which the piston rods 42 and 43 can pass is controlled by the adjustment of the lock nuts 46 on the lower end of the piston rods. Upon the gripping cylinders being brought to proper position outside of the ends of the axle blanks pressure is admitted to the cylinders 27 and 28 through the three-way valve 60 and pipe line 37 so

that the gripping devices 29 are driven into the ends of the axle blank 69. The fluid is thereupon exhausted by means of the three-way valve from the cylinders 40 and 41, 5 which has the effect of allowing the rear ends of the levers 22 and 23 to be lowered because of the counter-weights 24 and 25 then lifting the axle blank off the V-supports 63 and 64. Pressure is thereupon admitted to 10 the rear end of the cylinder 48 and behind the piston 50 through the pipe line 55 until the axle blank is moved into first forging position between the forging dies 66 and 67. Because of the lowering of the rear ends of 15 the levers 22 and 23 the axle blank is raised to a sufficient distance to pass out of the V-shaped holders 63 and 64 and over the inner edge of the dies 66 and 67. Upon being brought to the proper forging position 20 between the dies 66 and 67 pressure is again admitted through the cylinders 40 and 41 respectively so the levers 22 and 23 are elevated, bringing the axle blank downward to a slight degree, the forging process 25 thereupon commences which forces the upper die down upon the blank and continuing until the forging dies are in contact with each other. A suitable number of strokes 30 of the press is given while at the same time the axle blank 70 is rotated by means of the hand wheel 23 on the end of the shaft 31. This process is continued until the top and bottom dies come in contact. Thereupon the 35 pressure is exhausted from the cylinders 40 and 41 allowing the levers 22 and 23 to drop down, the counter-weights being sufficient to raise the axle blank and the blank is moved to the second forging position 40 between the dies by means of the cylinders 48 acting upon the sliding table 17 when the same operation as heretofore described is continued and the forging operation completed. After the completion of the 45 forging operation the pressure is again exhausted from the cylinders 40 and 41 and more pressure admitted to the double acting cylinder 48 by the four-way valve 62 through the pipe 55 and the completed axle carried to a position above the skids 68 and 50 69. The pressure is released from the gripping cylinders 27 and 28, thus releasing the axle blank on to the skids 68 and 69. The pressure is thereupon released from the rear of the cylinder 48 through the pipe 55 and pressure admitted through the supply pipe 56 by means of the four-way valve 62 to the forward end of the cylinder 48, thus bringing the sliding table 17 back on to the 55 frame and into position to pick up a second blank.

I propose to operate the pistons in the various cylinders and maintain a uniform pressure on the operating cylinders and particularly the gripping cylinders 27 and 28 by means of compressed air contained in a tank

75 from which a supply line 76 leads to a header 77 from which header small pipes lead to the valves 60, 61 and 62 respectively. The length of the axial blank will increase 70 during the forging operation and the fluid pressure in the cylinders 27 and 28 will allow this expansion to take place so that by allowing the valve 60 to remain open during the forging operation the pressure is maintained upon the pistons in the cylinders 27 75 and 28.

It will be thus understood that during the forging operation the blank is in contact with the dies only during the actual forging operation and that with each stroke of the dies the axle is lifted upward from the lower die until the levers 22 and 23 rest upon the ends of the piston rods 42 and 43, so that the loss of heat by reason of the axle coming 80 in contact with the dies is reduced to a minimum. The axle blank is, of course, under control of the operators at all times without the usual handling of the axle blank by means of tongs as has been the practice 85 heretofore.

While I have described more or less precisely the details of construction, I do not wish to be understood as limiting myself thereto, as I contemplate changes in form 90 and the proportion of parts and the substitution of equivalents as circumstances may suggest or render expedient without departing from the spirit or scope of my invention.

I claim:

1. In combination, a forging press having 100 upper and lower dies, the manipulating mechanism comprising a movable frame, means mounted upon the frame for holding the work piece in position during the forging operation and moving it to different positions during the said operation, the said means also being adapted to hold the work piece suspended between the upper and lower dies when the force of the upper die is removed from the said work piece. 105

2. In combination, a forging press, forging dies mounted in said press, a manipulating mechanism comprising a frame, a movable table mounted upon said frame, and means secured to said table for holding a 110 metal blank during the forging operation, whereby a metal blank is lifted out of contact with the lower forging die at each forging operation.

3. In combination, a forging press, forging dies mounted in said press, a manipulating mechanism comprising a frame, a sliding table mounted upon said frame, means for moving the sliding table, a pair of pivotally mounted levers upon said table, a pair 115 of cylinders mounted upon the ends of said levers, and gripping pistons mounted within said cylinders.

4. In combination with a forge press, a 120 plurality of dies mounted in said press, a 125

4
manipulating mechanism comprising a frame, a sliding table mounted upon said frame, a pair of pivotally mounted arms secured to said table, means for raising and lowering said arms, gripping means secured to said arms, and means for moving said sliding table on the frame.

5. In combination with a forge press having upper and lower forging dies, a manipulating mechanism comprising a frame, a movable table upon said frame, means for actuating the said table, a pair of counterbalanced pivotally mounted arms secured to said table, means carried by said arms whereby a metal blank is held in position between the dies during the forging operation, said counterbalanced arms adapted to lift the blank out of contact after each forging operation and to hold the blank out of contact therewith until the next forging operation.

6. In combination with a forging press having upper and lower forging dies, a frame, a movable table mounted thereon, a pair of pivotally mounted arms secured to said table, means at the forward end of said arms for holding a metal blank, means for moving the said table and adjustable counterweights secured to the rear ends of said arms.

7. In combination with a forging press having upper and lower forging dies, a frame, a movable table mounted upon said frame, a pair of pivotally mounted arms secured to said table, adjustable counterweights secured to the rear ends of said arms, cylinders having gripping pistons therein secured to the forward ends of said arms and means secured to the said table adapted to move a metal blank to differently adjusted positions in a forging press.

8. In combination, a manipulating mechanism comprising a frame, a movable table upon said frame, a pair of pivotally mounted arms secured to the said table, a pair of

cylinders having gripping pistons therein carried by the said arms, means for moving the said table upon the said frame and a pair of cylinders adapted to move the said arms when a fluid pressure is admitted to the said cylinders.

9. In combination, a manipulating mechanism comprising a frame, a movable table mounted thereon, a cylinder mounted upon said frame, a piston carried by said cylinder and connected to said movable table, a pair of pivotally mounted arms upon said table, cylinders carried by said arms, means carried by said cylinders adapted to grip a metal blank, counterweights upon said pivoted arms and cylinders carried by said frames adapted to manipulate the said pivoted arms.

10. In combination, a manipulating mechanism comprising a frame, a movable table mounted thereon, a pair of pivotally mounted arms secured to the said table, counterweights on the rear ends of said arms, cylinders having gripping pistons therein carried by the forward ends of the said arms, pistons carried by said cylinders adapted to grip a metal blank and having means extending through the rear of the said cylinders whereby the pistons may be rotated.

11. In combination, a manipulating mechanism comprising a frame, a movable table mounted thereon, a pair of pivotally mounted arms secured to said table, means at the forward ends of said arms for gripping a metal blank, a cylinder carried by said frame, a piston mounted therein and secured to said movable table, a pair of cylinders carried by said table having pistons mounted therein and adapted to tilt the pivotally mounted arms and means for controlling the admission of a fluid pressure to said cylinders.

Signed at Chicago, Illinois, this 26th day of September, 1919.

CHRISTOPHER WEATHERSON.
